UNITED STATES PATENT OFFICE.

RALPH L. HARDEN, OF ATTLEBORO FALLS, MASSACHUSETTS, ASSIGNOR TO THE MASON BOX COMPANY, OF ATTLEBORO FALLS, MASSACHUSETTS, A CORPORATION OF MASSACHUSETTS.

MAILING BOX.

Application filed March 26, 1926. Serial No. 97,581.

Heretofore it has been proposed to attach an envelope to a box or package or to the wrapper therefor so that a letter may be mailed together with the contents of the box or package, but the methods proposed have been objectionable for various reasons, chief of which are that the letters are likely to become detached which has resulted in postal regulations requiring separate addresses for letter and package.

Objects of the present invention are to provide a combined envelope and box in which a part or all of the envelope is an integral part of the box so that a single address will serve for both letter and box, the envelope preferably having a window so that the address on the letter or other enclosure will serve a three-fold purpose, namely, as an address at the head of the letter within the envelope, an address for the envelope, and an address for the box.

The nature and scope of the invention will be evident from the following description and the appended claims, with reference to the exemplary embodiments illustrated in the accompanying drawings in which:

Fig. 1 is a front view of a box embodying the invention;

Fig. 2 is a section on line 2—2 of Fig. 1;

Fig. 3 is a similar section of a modified form of the invention;

Fig. 4 is a section on line 4—4 of Fig. 1;

Fig. 5 is a horizontal fragmentary section through one of the front corners of a cover embodying the invention;

Fig. 6 is a development of the integral piece of material forming the box cover and envelope as constructed in Figs. 1, 2, 4 and 5;

Fig. 7 is a section similar to Figs. 2 and 3 but showing a further modification;

Fig. 8 is a plan view of a further modification; and

Fig. 9 is a development of the integral sheet of paper forming the box cover and envelope of the form shown in Fig. 8.

The particular embodiment shown in Figs. 1, 2 and 4 comprises a box 1, a cover 5 telescoping over the box with metallic tongues 3 fast to the box and extending through slots

50 4 in the cover, these tongues being flexible to bend over the sides of the cover detachably to secure the cover on the box, and an envelope comprising a back 6, a front 8, and a closure

flap 14, the front having an address window 16 closed by a piece of transparent material 17, and a slot 15 under flap 14 through which the letter (or other enclosure) may be inserted into the envelope.

The back 6 covers the entire outer surface of the cover 5 and is folded inwardly around all four edges of the cover as shown at 7, the back is cemented to the cover at least around its periphery and preferably throughout its entire area, thereby serving not only as the back of the envelope but also as a reinforcement and finish for the box cover throughout the entire outer surface of the cover including the corners and lower edges. If desired, the front of the envelope may also extend over the sides of the cover and fold upwardly on the inside, at least on three sides, as shown at 10 and 11 in Figs. 2 and 4, thereby further reinforcing the cover and avoiding exposed edges, in which case the envelope front is cemented to the back throughout its entire area except the pocket area outlined at 19 in Fig. 1. However, the envelope front may terminate at the ends of the top surface of the cover as indicated at 8' in Fig. 3, although even in this case the front preferably folds under the cover at the margin opposite the flap as illustrated at 11 in Fig. 4.

For clarity of illustration strips of cement are indicated only at 9 in Figs. 2 and 4 and at 12 in Fig. 3, but from the foregoing it will be understood that the cement is not confined to these areas.

While the front and back of the envelope may be formed of separate sheets they are preferably formed from a single sheet integrally joined together at the fold 2 (Fig. 4) instead of having cut edges at the fold line 2. Thus the entire envelope is formed from a single integral blank and is integrally cemented to the box cover throughout the entire outer area of the cover and part of the inner area, both at the front and the back folding around the edge of the cover along the side of the cover opposite the flap.

The flap is preferably gummed on its under side in the usual way and a stamp mark may be provided on the flap as shown at 18.

As shown in Fig. 5, the cardboard form 5 has cemented thereover on the outside of each corner a reinforcing strip 20, then the back portion 6 of the blank which has portions 6'

cemented on the outside of form 5 and thence bent over the edges as shown at 7. Portions 6' and 7 are extended outwardly at each end of two opposite sides to form tabs 6² (Figs. 5 and 6) which are adapted to fit around, finish and reinforce the corner as shown in Fig. 5.

The front 8 of the envelope is similarly provided with portions 8' which are cemented 10 to the sides of the cover over parts 6' as shown in Fig. 5, and have tabs 8² adapted to reinforce and finish the corners as seen in Fig. 5. The development of the whole cover and envelope is shown in Fig. 6 to illustrate the preferred construction and method of folding the blank.

Fig. 7 shows an embodiment of the invention in which the sides 8³ of the envelope are not cemented inside the sides of the cover 20 as shown in Fig. 2, but are made longer, left loose and gummed for attachment to the bottom of the box to hold it in closed position. With this exception the construction is the same as that shown and described for the embodiment shown in Figs. 1, 2, 4 and 5.

Fig. 8 shows another embodiment of the invention in which the envelope front 20 covers only a part of the box top, leaving a marginal edge 21 on either side and a wider portion 22 adjacent to the top of the envelope. Stamps 23 for the postage of the box may be affixed to this portion 22, while stamp 18 is affixed to the flap of the envelope for the envelope postage.

A development of an integral sheet of paper forming the cover for the top of the box and the front and back of the envelope is shown on Fig. 9. This differs from the development shown on Fig. 6 in that the sides 24 of the bottom portion of the envelope are extended outwardly and gummed on the back at their ends for sealing the box in a manner similar to that shown at 8³ on Fig. 7. The other two sides 25 are provided with tabs 26 similar 45 to tabs 6² and 8² on Figs. 5 and 6. The front 20 of the envelope is affixed to the back at the fold line 2' similar to fold line 2 described above. The front 20 is different from the front 8 only in that it is narrower as shown 50 on Figs. 8 and 9.

By the use of the device of this invention, the paper cover which is customarily applied over pasteboard boxes to provide a finish and to strengthen the carriers, may be omitted, 55 from the cover, inasmuch as the envelope folds over the edges of the cover and serves the double function of an envelope back and a covering for the pasteboard.

It is obvious that various modifications of 60 the embodiment shown might be resorted to, and, therefore, I do not wish to be limited except by the scope of the appended claims.

I claim:

1. An article of the character described 65 comprising a box in two parts having sides

telescoping together, an envelope cemented to one part with its back extending around the sides to a line concealed by the other part when the two parts are telescoped together.

2. An article of the character described 70 comprising a box in two parts having sides adapted to be telescoped together, an envelope having front and back portions and being fastened to one of said parts, one of the portions of said envelope extending around 75 one side of one part of the box to a line concealed by the other part of the box when the two parts are telescoped together.

3. An article of the character described 80 comprising a box provided with a cover having at least one side overlapping the box, an envelope cemented to the cover with its back extending over the cover adjacent said side, thence along said side, and thence folded 85 along the inner face of said side.

4. An article of the character described 90 comprising a box made of a container part and a cover part, an envelope cemented to the cover part and having back and front portions, the back portion being fast to the cover of the box and the front portion being cemented at its edges to the cover of the box and having at least one margin overlapping the edge of the cover and continued to a line inside the cover which is concealed when the cover is in position on the container, and another margin loose from the back and forming the flap of said envelope.

5. An article of the character described 100 comprising a box made up of a container part and a cover part adapted to be held together in closed position by flexible metal clips attached to said container part, and extending through suitable apertures in said cover part, and thence bent over to lock the cover, an envelope having front and back portions, the back portion being fast to said cover, and the front portion being cemented thereto at its edges and extending over said apertures, whereby the clips in the closed position of 105 said box serve also to hold the parts of the envelope together.

6. An article of the character described, a box in two parts having sides telescoping together, an envelope having top and bottom portions, said bottom portion adapted to be cemented to one part of the box, and having all of its sides extending over the side of the part of said box to which it is attached to lines which are concealed by the other part of the box when the parts are telescoped together, and the top portion of the envelope having at least one of its sides extending to substantially the same line and another side forming the flap of the envelope.

7. An article of the character described, a box in two parts having sides telescoping together and flexible metal clips attached to the lower part of the box and adapted to be extended through apertures in the upper part 120 125 130

to hold the box in closed position, a window envelope having top and bottom portions, the bottom portion adapted to be cemented to the upper part of the box, and having all of its sides extending over the side of the part of the box to which it is attached to lines which are concealed by the other part of the box when the parts are telescoped together, and the top portion of the envelope having at least one of its sides extending to substantially the same line and another side forming the flap of the envelope.

8. An article of the character described comprising a container and a cover, flexible metal clips extending from the container through the cover, and an envelope on the cover, said clips also extending through marginal portions of the envelope.

9. An article of the character described comprising a box in two parts having sides telescoping together, an envelope having front and back portions integrally united along a fold line, the envelope being cemented to one of said parts with said fold line con-

cealed by the other part when the two parts are telescoped together.

10. An article of the character described comprising a box in two parts having sides telescoping together, an envelope having front and back portions made of a single sheet of paper folded so that one part forms the back of the envelope and a covering for one part of the box, and the other part of the folded sheet forms the front and flap of the envelope, both parts of the envelope having at least one portion extending around the sides of the box to reinforce and finish them.

11. An article of the character described, comprising a box formed of sheet material in two parts with their sides telescoping together, the sheet material of one of the parts of said box being covered with paper, and a paper envelope on said part of the box, a portion of the paper of the envelope forming a part of the paper covering of the box part.

Signed by me at Attleboro Falls, Massachusetts, this third day of March 1926.

RALPH L. HARDEN.
